UNITED STATES PATENT OFFICE.

FREDERICK H. KINDL, OF PITTSBURGH, PENNSYLVANIA; F. H. KINDL, JR., ADMINISTRATOR OF SAID FREDERICK H. KINDL, DECEASED.

LOADING APPARATUS.

1,097,759.

Specification of Letters Patent. Patented May 26, 1914.

Application filed June 21, 1913. Serial No. 774,997.

To all whom it may concern:

Be it known that I, FREDERICK H. KINDL, a citizen of the United States, residing at Pittsburgh, in the county of Allegheny and State of Pennsylvania, have invented a new and useful Improvement in Loading Apparatus, of which the following is a full, clear, and exact description, reference being had to the accompanying drawings, forming 10 part of this specification, in which—

Figure 1 is a side elevation, partly diagrammatic, of loading apparatus embodying my invention. Fig. 2 is a side elevation partly broken away, of a portion of the apparatus. Fig. 2^a is a diagrammatic side elevation showing a modification. Fig. 2^b is a side view showing another modification of a portion of the apparatus. Fig. 3 is a view partly in elevation and partly in 20 section of another portion of the apparatus. Fig. 4 is a vertical section of a portion of the jointed chute. Fig. 5 is a section on the line V—V of Fig. 3. Fig. 6 is a view, partly in section and partly in elevation, 25 the plane of the section being on the line VI—VI of Fig. 2, and Fig. 7 is a similar view, the plane of the section being on the line VII—VII of Fig. 2.

My invention has relation to loading apparatus, and more particularly to apparatus 30 for loading material such as coal, ore and the like into the holds of vessels.

The object of my invention is to provide loading apparatus of this character which 35 can be readily manipulated to meet the requirements of its use and by means of which the material can be rapidly handled and loaded.

The nature of my invention will be best 40 understood by reference to the accompanying drawings, in which I have shown the preferred embodiment thereof, and which will now be described, it being premised, however, that various changes can be made 45 in the details of construction and arrangement of the parts without departing from the spirit and scope of my invention as defined in the appended claims. In these drawings, the numeral 2 designates a traveling crane mounted on the tracks 3 and having the vertical tower portion 4 and the upwardly extending over-hanging boom 5. This boom comprises a hollow rectangular frame work of any suitable construction 55 and within which is mounted to travel a

hoisting bucket 6. The lower end portion of the boom is provided with trunnions 7 which are provided with suitable bearings 8 in the fixed supports 9. The boom is held at the desired angular elevation by 60 means of a cable 10 passing around a pulley 11 near the upper end of the boom and around the pulley 12 at the upper end of the tower 4, and thence downwardly to a winding drum 13 driven by a suitable motor 14. By means of this motor and the pivotal mounting of the boom, in the manner described, the latter can be held in any desired angular position. Trunnioned 65 within the lower end portion of the boom is a rotary bucket carrier 15, which is generally somewhat similar to the rotary carrier which forms a part of the apparatus of my Patent No. 711,772, of October 21, 1902. This carrier forms a seat for the 70 bucket 6 when the latter is in filling position at the lower end of the boom. The bucket is lowered into this carrier and the carrier is then rotated to bring the bucket into filling relation to the discharge 17 of a 75 suitable hopper, bin or storage receptacle 18, which is mounted on and carried by the traveling crane 2. The lower portion of the boom has secured thereto the guide members 20 formed with grooves 21 to receive 80 and guide the trunnions 22 of the bucket. Each of these guide grooves has an opening 23 to enter and release the trunnions when the bucket and carrier are in the positions shown in Fig. 2. Inasmuch as the bucket 85 and carrier are required to make only a part of a complete revolution, it is not necessary to disengage the bail from the bucket. I may, therefore, cut away the 90 guides for the bail, as indicated at 23^a in Fig. 2^b to permit the bail 16 to move with the bucket 6^a to the position shown in dotted lines. The trunnion guides 23^b instead of being circular as in my said patent, (and as are the guides in Fig. 2) may be 100 of short arcuate form.

In order to rotate the carrier from the position shown in Fig. 2 to a position in which the open end 24 of the bucket will be opposite the discharge 17 of the hopper, 105 the carrier is provided at each side with a gear segment 25. These segments are relatively engaged by gears 26 driven by pinions 27 on the armature shaft 28 of an electric motor 29.

30 designates an adjustable gate for the discharge 17.

31 is the hoisting rope or cable attached to the bail 16 of the bucket and passing over 5 a pulley 32 at the upper end of the boom and thence downwardly to a winding drum 33 mounted on the boom and driven by an electric motor 34 through suitable gears 35.

36 designates a carriage which is mounted 10 for movement on the boom on the wheels or rollers 37, as best shown in Fig. 3. This carriage is provided with the brackets 38 having stop portions 39 which are designed to be engaged by studs or projections 40 on 15 the bucket when the latter is raised within said carriage to the position shown in Fig. 3. This engagement causes the bucket to be tilted into the discharge position shown in dotted lines in Fig. 3. The bucket in this 20 position discharges on to the inclined portion 41 of the carriage which terminates in a short vertical discharge chute 42. Pivoted to this discharge chute 42 is a chute section 43; and pivoted to the lower end section 43 is 25 another chute section 44. The pivot 45 which connects the two sections 43 and 44 is at substantially right angles to the pivot 46 which connects the section 43 to the chute 42. This gives the chute a universal movement 30 by means of which it can be swung into any desired position. For the purpose of manipulating this chute, I provide the pivot shafts 46 with sprocket gears 47 engaged by actuating chains 48. These chains pass 35 around sprocket pinions 49 on a shaft 50 which is driven through suitable gearing 51 from an electric motor 52 mounted on the carriage 36.

53 designates a winding drum operated by 40 a motor 54 for raising and lowering the carriage 36 on the boom. A rope or cable 54^a passes from the drum 53 over a pulley on the same shaft as the pulley 32 and over another pulley 55 at the end of the boom and thence 45 to a sheave or pulley 56 on the carriage 36.

Instead of mounting the motors 34 and 54 and their winding drums and gearing on the boom, I may place these parts on the platform 2^a of the crane, as shown in Fig. 2^a.

50 The operation is as follows: The bucket is lowered by means of the motor 34 into the rotary holder in the position shown in Fig. 2. The holder is rotated by the motor 29 to bring the open end of the bucket opposite the discharge 17. After the bucket is filled from the hopper 18 it is returned to the position shown in Fig. 2 and hoisted to dumping position. The motor 34 is then operated to raise the bucket to the position shown in 55 Fig. 3 and tilt and dump it.

Where the apparatus is used for loading ships, as illustrated in Fig. 1, the sectional chute 43 and 44 depends through a hatchway into the hold of the ship. By proper 60 manipulation of the jointed chute sections

the spaces between hatchways can be properly filled.

In order to clear the masts or other superstructure of the ship in bringing the apparatus to loading position, the boom can be 70 swung upwardly on its trunnions to a position such as that indicated in dotted lines in Fig. 1. In the event of spars or other superstructures which cannot be cleared in this manner, the boom can be readily made with 75 one or more telescopic sections so that it can be shortened while swinging it into and out of operative position. The entire crane can be moved along the dock from one hatchway to another or from one ship to another; and 80 the carriage 36 can be moved on the boom so as to bring the discharge chute in proper relation to a hatchway.

My invention provides loading apparatus 85 which can be readily manipulated and by means of which material can be rapidly handled and loaded. It will be understood that the material to be loaded can be delivered into the hopper 18 in any suitable manner. For instance, the crane can be run under a 90 car dumping apparatus and the contents of a freight car directly dumped into the hopper; or it may be supplied in any other suitable way.

I also desire it to be understood that various changes can be made in the construction 95 of the crane and its boom; also in the details of the rotary carriage, and that various other changes may be made in the construction and arrangement of the parts within 100 the scope of my invention.

What I claim is:

1. Loading apparatus comprising a crane, a hopper mounted thereon, a boom carried by the crane, a bucket mounted for traveling on the boom, a rotary bucket holder also mounted on the boom and adapted to receive the bucket, and means for rotating said holder to carry the bucket in filling relation to the hopper and back into position 105 to be elevated on the boom; substantially as described.

2. Loading apparatus comprising a traveling crane having a hopper or bin, a boom pivoted thereto, a bucket mounted to travel 110 on the boom, actuating means for the bucket, a rotary holder for the bucket also mounted on the boom, and means for rotating said holder to move the bucket into filling relation to the hopper or bin and then back in 115 position to be moved on the boom; substantially as described.

3. Loading apparatus comprising a hopper or receptacle for the material to be loaded, an upwardly extending inclined boom, a bucket holder rotatably mounted in the lower portion of the boom, a bucket arranged to travel on the boom and to be moved into and out of the holder, and means for rotating the holder to bring the bucket 125 130

into filling relation to the receptacle and back into position to be raised on the boom; substantially as described.

4. Loading apparatus comprising a traveling crane having a storage receptacle thereon, an inclined boom pivoted to the crane, means for moving the boom to different angular positions, a bucket mounted to travel on the boom, a bucket holder pivotally mounted on the boom and arranged to receive the bucket, and means for rotating the bucket holder to move the bucket into filling relation to the receptacle and back into position to be raised on the boom; substantially as described.

5. Loading apparatus comprising a traveling crane having a storage receptacle and an inclined over-hanging boom, a bucket holder pivoted on the boom, means for actuating the holder to move the bucket into filling relation with the receptacle and back into position to be raised on the boom, a carriage mounted for travel on the boom and into which the bucket is adapted to be raised, said carriage having means for engaging and effecting a dumping movement of the bucket; substantially as described.

6. Loading apparatus comprising a traveling crane having a storage receptacle and an inclined over-hanging boom, a bucket holder pivoted on the boom, means for actuating the holder to move the bucket into filling relation with the receptacle and back into position to be raised on the boom, a carriage mounted for travel on the boom and into which the bucket is adapted to be raised, said carriage having means for engaging and effecting a dumping movement of the bucket, and also having a jointed discharge chute; substantially as described.

7. Apparatus of the character described, comprising a swinging boom, a bucket mounted for travel on said boom, a movable bucket holder at the base of the boom, the bucket being movable into and out of the

holder and also movable therewith, and a receptacle arranged to discharge into the bucket when the latter is moved with the carrier into proper relation to the receptacle; substantially as described.

8. Apparatus of the character described, comprising a structure having a bucket runway, a bucket mounted for travel on said runway, a movable bucket holder at the base of the runway, the bucket being movable into and out of the holder and also movable therewith, and a receptacle arranged to discharge into the bucket when the latter is moved with the holder into proper relation to the receptacle, substantially as described.

9. Apparatus of the character described, comprising a structure having a bucket runway, a bucket mounted for travel on said runway, a movable bucket holder at the base of the runway, the bucket being movable into and out of the holder and also movable therewith, a receptacle arranged to discharge into the bucket when the latter is moved with the holder into proper relation with the receptacle, and means for controlling the discharge from the receptacle into the bucket; substantially as described.

10. Apparatus of the character described, comprising a structure having a bucket runway, a bucket mounted for travel on said runway, a bucket holder at the base of the runway, the bucket being movable into and out of the holder and also movable therein, a storage receptacle arranged to discharge into the bucket when in the holder, and a chute adjustably mounted on the runway structure and into which the bucket is arranged to discharge when elevated on the runway; substantially as described.

In testimony whereof, I have hereunto set my hand.

FREDERICK H. KINDL.
